Attorney

UNITED STATES PATENT OFFICE.

JOSEPH Y. PISCEK, OF GALLUP, NEW MEXICO.

RAILROAD-TRACK CONSTRUCTION.

1,381,499.

Specification of Letters Patent. Patented June 14, 1921.

Application filed January 6, 1921. Serial No. 435,374.

To all whom it may concern:

Be it known that I, JOSEPH Y. PISCEK, citizen of Czechoslovakia, residing at Gallup, in the county of McKinley and State 5 of New Mexico, have invented certain new and useful Improvements in Railroad-Track Constructions, of which the following is a specification.

This invention relates generally to railroad track construction, having more particular reference to the securing of the rails to the ties, and the fastening means for the rail joints.

The invention has for an object to provide 15 a simplified rail joint construction in which a common fastening means secures the two ends of the rails to the tie and also locks them firmly together.

For further comprehension of the invention, and of the objects and advantages thereof, reference will be had to the following description and accompanying drawings, and to the appended claims in which the various novel features of the invention 25 are more particularly set forth.

Figure 1 of the drawings is a plan view of a portion of a railroad track having the rails secured in place according to the invention.

30 Fig. 2 is a side elevation thereof.

Fig. 3 is a transverse section on the line 3—3 of Fig. 1.

Fig. 4 is a detail perspective view showing the fastening devices employed.

35 Fig. 5 is a fragmentary horizontal section on the line 5—5 of Fig. 2.

Referring now to the drawings the numerals 10, 10', and 10^a indicate adjacent track rails which, between the ends, are 40 formed in the usual manner. At their ends these rails are formed on opposite sides with integral ribs 11, 11' which are preferably flush at their sides with the sides of the rail treads and extend between the latter and the 45 feet of the rails, projecting laterally on opposite sides of the webs of the rails.

The rails are laid to have their adjacent ends rest on specially formed ties 12 provided with recesses 13 on their upper faces 50 adapted to receive the rails and their fastening blocks, these recesses extending from side to side of the ties. On the inner sides of the rails the walls of these recesses are undercut to receive one side of the feet of the 55 rails, the inner walls of the recesses thus presenting tongues 13' which project over

the feet and against the ends of which the inner faces of the webs abut.

The outer walls of the recesses are preferably cut square to permit of ready insertion of fastening blocks 15, 15' which are arranged in contacting pairs transversely of the ties, these blocks being of a length to have a tight fit between the outer walls of the recesses 13 and the outer faces of the 60 rail webs, while the inner ends thereof are undercut as at 16 to fit over the rail flanges, the inner ends of these blocks and the recesses 13 thus jointly forming a socket in which the rail fits tightly and which is 65 shaped complementary to the lower part of the rail. The tongues 13 and blocks 15, 15' are also arranged to have a locking engagement with the ribs 11, 11' on the rail ends, being formed with notches 13^a and 15^a re- 70 spectively on their rail engaging ends which receive the ribs, the side walls of these notches closely inclosing the united ribs.

These blocks 15, 15' may be secured in place by bolts 18 passing downwardly 80 through holes 19 therein and screwed into bushings 20 inserted in suitable recesses in the undersides of the ties. As here shown, these bushings may be of oblong rectangular shape in plan view and having their side 85 walls inclining upwardly toward one another.

Between the ties 12 the rails may be secured to narrower ties 25 provided with recesses similar to the recesses 13 in which are 90 located blocks 26 having their rail engaging ends undercut as at 27 to fit over the feet of the rails, these blocks being secured in place similarly to the blocks 15, 15'.

Having thus described my invention what 95 I claim as new and desire to protect by Letters Patent of the United States is as follows:

1. In combination, track rails having laterally projecting ribs at their ends, ties on 100 which the rail ends rest, and blocks secured on said ties and having members projecting over the feet of the rails on opposite sides of the said ribs.

2. In combination, track rails having laterally projecting ribs at their ends on opposite sides of the webs thereof and extending between the treads and feet of the rails, ties on which the said rail ends rest, and blocks secured on said ties and having members 110 projecting transversely over the said feet on opposite sides of the said ribs.

3. In combination, track rails having laterally projecting ribs at their ends on opposite sides of the webs thereof and extending between the treads and feet of the rails, ties 5 on which the said rail ends rest, and blocks secured on said ties and having members projecting transversely over the said feet on opposite sides of the said ribs, said blocks being arranged in pairs transversely of the 10 ties with their adjacent edges contacting and in line with the meeting ends of the rails, said adjacent edges being notched at the rail engaging ends of the blocks to accommodate the said ribs.
- 15 4. In combination, track rails having laterally projecting ribs at their ends on opposite sides of the webs thereof and extending between the treads and feet of the rails, ties on which the said rail ends rest, and blocks 20 secured on said ties and having members projecting transversely over the said feet on opposite sides of the said ribs, said ties being recessed to receive the said rails and blocks, the inner walls of said recess being undercut

to receive the inwardly extending side of the 25 rail foot.

5. In combination, track rails having laterally projecting ribs at their ends on opposite sides of the webs thereof and extending between the treads and feet of the rails, ties 30 on which the said rail ends rest, and blocks secured on said ties and having members projecting transversely over the said feet on opposite sides of the said ribs, said ties being recessed to receive the said rails and 35 blocks, the inner walls of said recesses being undercut to receive the inwardly extending side of the rail foot, bolts passing downwardly through said blocks to secure them to the ties, and bushings through which said 40 bolts are threaded, said bushings being inserted in recesses in the undersides of the ties, and being of oblong rectangular shape in plan view with their sides inclining upwardly toward each other. 45

In testimony whereof I have affixed my signature.

JOSEPH Y. PISCEK.
